UNITED STATES PATENT OFFICE.

ROBERT BOSCH, OF STUTTGART, GERMANY.

BENZIN-WASHSTAND.

1,143,354.

Specification of Letters Patent. Patented June 15, 1915.

Application filed September 23, 1910. Serial No. 524,219.

To all whom it may concern:

Be it known that I, ROBERT BOSCH, a subject of the Emperor of Germany, and residing at Stuttgart, Germany, have invented certain new and useful Improvements in Benzin-Washstands; and I do hereby declare the following to be a full, clear, and exact description of the invention, such as will enable others skilled in the art to which it appertains to make and use the same.

The invention relates to a safety washstand for washing with benzin and other inflammable liquids in which a vessel filled with sand, ashes or the like is placed over the wash basin, and arranged so that it opens automatically and empties its contents over the wash basin when the benzin contained therein ignites. For this purpose, according to the invention, the sand box is provided with folding bottom plates which are supported by two levers held together by a string made of easily inflammable material. Should the benzin ignite, the flame would burst upward and ignite the cord, so that the lever will fly upward and release the two bottom plates.

In order to avoid the splashing of the benzin and outburst of the flame, upon opening the folding lids, a sieve is provided above the folding lids, which retards the descent of the sand and prevents it from dropping too suddenly on the working table. In place of a sieve a protecting wall of tin or the like may be attached to the washstand, the wall being automatically drawn up the instant the folding bottom plates are lowered so that the benzin holder is shut off from the outside. In order to further insure safety, the washbasin is preferably supported on a perforated tin plate, so that all superfluous or splashing benzin may drain off through a funnel secured beneath the tin plate into a non-explosive can below.

45 In the drawings, Figure 1 represents a front view partly in section; Fig. 2 a side view, partly in section; Fig. 3 is a cross-section on line 3—3 of Fig. 2.

A is a washbasin resting on a perforated 50 tin plate B which rests on brackets C. The benzin, which during the washing operation spills or drains off, flows through a funnel D into the non-explosive can E.

F is a closed chest or box, whose bottom 55 K is a sieve. The bottom is sealed from beneath by two lids J and J₁ attached at

the sides thereof, and whose inner edges rest on the flat heads I I₁ of the shorter arms of two angle levers H H. The longer arms of the two angle levers H H are connected together at their lower ends by an easily ignitable string G. The chest or box F is filled with sifted dry sand, ashes or other non-inflammable material, such that it will flow unhindered through the sieve K 60 as soon as the lids J and J₁ drop down. When the benzin in the vessel A ignites, the flames burst upward and burn the string G which holds down the two levers H H. The levers are therefore free to shoot upward in the direction of the arrows, and the two folding bottom plates J and J₁ swing down, so that the sand drops through the sieve K and extinguishes the fire.

On both sides of the washstand, beneath 70 the lower ends of levers H H, are journaled the rods M₁, on which the upwardly extending arms L are fastened in such manner that they project in the path of travel of levers H H. At the front of the washstand 75 on the rods M₁ are latches L₁. The noses of the latches lie in corresponding notches in pull rods N which are slidably mounted on the frame of the washstand. The rods N carry weights Q and are suspended by 80 strings S₁ S₁, which are led over small pulleys S S and carry a vertically movable screen Q guided by stationary rods U. On the lower guiding brackets, in which the rods N N slide, coiled springs P are 85 preferably employed. When the string G is burned, the levers H H are disconnected and swing upward due to the weight of the sand loaded on the bottom plates J J₁. On their travel they turn the arms L and the rods M₁, 90 and thereby release the latches L₁. Then the rods N N with the weights O O drop down, their fall being cushioned by the springs P P, and pull the door or screen Q up to a stop V, so that they shut off the 95 compartment containing the washing vessel A. In order to guard nearby persons from the action of levers H H, bows W W are attached to both sides of the washstand. A shelf Z serves to hold working tools. A 100 glass window X may be provided in the compartment F for purpose of inspection. When several such washstands are located in one room, each is a separate unit and fire in one is immediately extinguished 105 without danger of communication to any other.

F is a closed chest or box, whose bottom 55 K is a sieve. The bottom is sealed from beneath by two lids J and J₁ attached at

I claim—

In combination with a washstand for washing with an inflammable liquid, a compartment above said washstand with a folding bottom, levers for normally holding said bottom in closed position, an easily ignitable material for normally holding said levers, a screen, a weight for closing said screen and a catch normally holding said screen in open position against the action of said weight,

the said levers being arranged to release said catch and said weight when said ignitable material burns; substantially as described.

In testimony whereof I affix my signature, 15
in presence of two witnesses.

ROBERT BOSCH.
